TOOL TRAY

Datus H. Maughan, Salt Lake City, Utah
(2994 S. Vista Circle, Bountiful, Utah 84010)

Filed May 14, 1971, Ser. No. 143,738

Term of patent 14 years

Int. Cl. D3—02

U.S. Cl. D87—1 R

FIG. 1

FIG. 2

FIG. 3

FIG. 4

FIG. 5

FIG. 1 is a perspective view of a tool tray showing my new design;

FIG. 2 is a side elevational view, the opposite side being substantially the same in appearance as the side shown;

FIG. 3 is an end elevational view, the opposite end being substantially the same in appearance as the end shown;

FIG. 4 is a top plan view; and

FIG. 5 is a bottom plan view thereof.

I claim:

The ornamental design for a tool tray, as shown and described.
